UNITED STATES PATENT OFFICE.

JOHN L. WHITE, OF LEONORE, ILLINOIS.

WATER-DISTRIBUTION SYSTEM.

SPECIFICATION forming part of Letters Patent No. 588,305, dated August 17, 1897.

Application filed March 9, 1897. Serial No. 626,620. (No model.)

To all whom it may concern:

Be it known that I, JOHN L. WHITE, of Leonore, Illinois, have invented certain new and useful Improvements in Water-Distribution Systems, of which the following is a specification.

This invention relates to a system for distributing water by means of pneumatic pressure, and is particularly adapted for use in distributing water, for example, to the different stories of a building, for fire protection, for sprinkling, and generally in situations where, by reason of remoteness from power, pressure cannot be obtained conveniently or economically.

While my invention is designed to meet the requirements of rural communities and for use in isolated situations, it can be applied generally wherever it is desired to supply water to one or more consumers under pressure adequate to raise it to the different stories of buildings for domestic use, for fire protection, or for sprinkling lawns, and the like.

My improved system comprises, in general terms, an engine, which, on the score of economy, may be a wind-engine or windmill, preferably connected to a pump adapted to supply both air and water, a receiver or reservoir to which air and water is supplied under pressure, and suitable connections, including pipes and valves, whereby both air and water may be forced into the reservoir or receiver and the water maintained under air-pressure either constant or variable, but sufficient in all cases to force the water out of the reservoir and distribute it as desired.

My preferred system or apparatus is shown in the accompanying drawings, in which—

Figure 1 is a diagrammatic view, including a side elevation, of a wind-engine arranged over a well and connected with a pump therein and showing also a receiver with its wall partly broken away to disclose a valve and float, and a building of several stories, which may be supplied with water. Fig. 2 is a detail showing a portion of the valve.

In the drawings, A indicates a windmill, which may be of any desired type or form and whose operating-rod B is connected with a suitable plunger working within the pump-cylinder C, the latter being arranged in a well and connected by the pipe D with the

reservoir E, arranged in any convenient relation to the engine and well. In the drawings the reservoir is shown placed below the 55 earth-surface, which is indicated at F, and in convenient proximity to the basement of the building G. The receiver is preferably placed below the ground, so that the water will not freeze. The water will be pumped 60 by the wind-engine into the reservoir, the water-level being indicated by the shade-lines in the drawings. Above the body of water the air contained in the reservoir will be compressed, and air may also be forced into the 65 reservoir through pipe D. The air-intake pipe is shown at I, and is a continuation of pipe H. In order to control the air-pressure, a valve h is placed in the pipe H and a float K is connected to the valve-stem, so that 70 when the water attains a certain elevation within the reservoir or tank the valve will be opened, air will be drawn in at the intake, and passing into the pump-cylinder at its lower end will be delivered out through 75 pipe D into the tank and more water will be pumped into the receiver, when the air-valve is again closed by the lowering of the float. The air delivered into the tank through pipe D will rise through the body of water and will 80 exert such pressure thereon as to force the water out—as, for example, through delivery-pipe L whenever a vent is opened in said pipe or its connections. As the water is drawn off the float descends, the valve is closed, and 85 more water admitted. By means of this simple apparatus, therefore, a constant supply of water is maintained within the tank or receiver under a sufficient air-pressure to force the water to a considerable elevation, the 90 height to which the water can be raised depending, of course, upon the stored pressure. The wind-engine may be provided with the usual governing devices, so as to throw it out of action when it is not desired to charge the 95 tank either with water or with air.

It will be observed that my system is entirely automatic, and the float may be so arranged as to control the relative proportions of air and water delivered into the tank. 100

My apparatus may be used without change in the principle to supply a single consumer or for more extended applications.

My system may be used with other forms of

pumping mechanism, and such pumping mechanism may be run by any form of engine.

The chief value of my invention resides in the fact that it is applicable to widely-varying conditions and avoids the expensive features of the systems now in vogue, which employ stand-pipes for obtaining a head of water sufficient to afford the requisite pressure, or, on the other hand, the expense attending upon running the pumps continuously to maintain the necessary pressure in the mains and distributing-pipes of a water system.

My invention further improves the quality of water because the liquid is constantly undergoing aeration.

I do not limit my invention to precise details of construction or arrangement of parts; but

I claim—

1. In a water-supply system, the combination, with a water-supply, of a pump for rais-

ing the water, an engine for operating the pump, a storage tank or reservoir into which the water is pumped, connections whereby the pump may be used for delivering both air and water into the tank, and means for automatically controlling the relative proportions of air and water delivered into the tank, substantially as described.

2. In a water-supply system the combination with a water-supply of a pump for raising the water, an engine for operating the pump, a storage tank or reservoir into which the water is pumped, connections whereby the pump may be used for delivering both air and water into the tank, a valve controlling the air-inlet and a float connected with the valve and operated by changes of the water-level, substantially as described.

JOHN L. WHITE.
